UNITED STATES PATENT OFFICE.

ERNST LINDNER, OF NEW YORK, N. Y.

DESIGN FOR A GAS-BURNER FIXTURE.

SPECIFICATION forming part of Design No. 27,654, dated September 21, 1897.

Application filed April 29, 1897. Serial No. 634,477. Term of patent 7 years.

To all whom it may concern:

Be it known that I, ERNST LINDNER, a citizen of the United States, residing at New York, in the county and State of New York, have invented and produced a new and original Design for an Incandescent-Gas-Burner Fixture, of which the following is a specification, reference being had to the accompanying drawing, forming part thereof.

10 The annexed drawing shows a view in elevation of an incandescent-gas-burner fixture embodying my design.

The object of the invention is to produce a new and original design for an incandescent-gas-burner fixture; and the invention consists in the configuration or shape of the burner-fixture, substantially as illustrated in the drawing.

20 The design for the burner-fixture comprises the globe-like portion A, which is divided into two parts by the rope-like ring a, the surface of the upper part being formed with a series of circumferential steps a' and the lower part

being perforated with a series of tear-like openings. At the bottom of the portion A is 25 a short cylindrical portion B, having at its end a rope-like ring b. Surmounting the globe-like portion A is the outwardly-flaring skeleton portion C, at the top of which is the disk-like part D, having a scalloped edge and 30 also a series of finger-like vertical portions d, of ornamental configuration.

The distinctive feature of the design is the globe-like portion A, divided into two parts, the upper part formed with a series of circumferential steps.

I claim—

The design for an incandescent-gas-burner fixture substantially as shown.

Signed at New York, N. Y., the 28th day 40 of April, 1897.

ERNST LINDNER.
